AUTOMATIC SALES APPARATUS

René Stra, Brussels, Belgium

Application October 23, 1936, Serial No. 107,140
In Belgium October 23, 1935

5 Claims. (Cl. 194—71)

My invention relates to the automatic distributing apparatus, working by the introduction of coins or of counters.

5 The main object of the invention is to permit the sale of a great variety of goods at different prices, without the necessity for the consumer to proceed to any previous adjusting manipulation of the coin mechanism of the apparatus, the payment being effected in introducing successively through one and the same slot for all the articles and whatever may be their price, a number of coins or of counters, the value or the size of which corresponds to the price of the article which has been chosen.

15 A second object of the invention is to ensure that the discharge of an article is prevented (blocked) so long as there has not been introduced into the apparatus a number of coins or of counters corresponding to the price of one of the articles in the compartment which has been brought in front of a distributing opening, common to all the articles.

20 A third object of the invention is to provide an apparatus having not too great dimensions and comprising receptacles the whole contents of which can be acquired by a single manipulation and payment (for instance for the selling of cold meats), and receptacles containing a plurality of articles such as cigarettes, chocolates 25 etc., which can be acquired individually and successively by prepayment for each article, said apparatus being adapted to distribute the articles contained in both types of receptacles through a single distributing opening.

25 A fourth object of the invention is to provide a distributing apparatus which comprises a plurality of receptacles for differently priced articles, respectively, and which can be used as an ordinary table (for restaurants, tea-rooms, etc.)

30 Another object of the invention is to reduce to a minimum and to group the projecting parts of the apparatus which are necessary for the manipulation of the apparatus so as to permit its utilization as an ordinary table. With this object in view, my invention essentially consists in the special arrangements and combinations of parts hereinafter fully described and pointed out in the annexed claims.

35 On the annexed drawings:

Figures 1, 2 and 3 show a distributing apparatus according to the invention and represent more especially a coin locking mechanism working with a variable number of coins. Figure 1 is a vertical cross-section, Figure 2 is a view par-

tially in plan and partially in horizontal cross-section. Figure 3 is a view of details.

Figures 4, 5, 6 show various embodiments of the device used for obturating with a variable amplitude the distributing opening. 5

Figures 7 to 12 show a series of forms of embodiments for the coin locking mechanism.

In the example shown, the apparatus forms the upper portion of a table and comprises a fixed casing 1 mounted on a column 1a and 10 closed at the top by a cover 3 provided with a glass 2.

15 Inside of the casing 1 is situated a rotating plate 4 which supports receptacles 5 radially arranged, the contents of which can be removed by the consumer by a single payment and receptacles 6 containing a plurality of articles adapted to be removed successively by a prepayment for each article.

The vertical edge of the casing 1 has a distributing aperture 7 which may be closed by a shutter 8.

20 The plate 4 can be rotated from the outside of the apparatus so as to bring one of the receptacles 5 or 6 containing the article which has been chosen by the consumer in front of the distributing aperture 7.

25 The device for actuating the plate 4 is situated in front of the shutter 8 and is supported by the drive of the shutter 8 with which it can be 30 bodily connected. The actuating means for the shutter 8 and the driving means for the plate 4 comprise a handwheel 16 which is supported by the shutter 8 and which acts, for instance by friction, on a roller 16a arranged at right angles 35 with respect to the handwheel and acting, for instance also by friction, on a flange 4¹ of the plate 4.

35 In consequence, when the hand wheel 16 is caused to be rotated, the plate 4 is also put in 40 rotation through the intermediary of the roller 16a.

The opening of the shutter 8 depends upon the actuating of a rod 17 which extends radially on the base of the casing 1 and which may be held 45 in the closed position of the shutter 8 by a coin locking device of the kind hereinafter described.

The rod 17 is provided at its extremity situated towards the centre of the apparatus with teeth 18 cooperating with an oscillating pawl 19 50 and terminated by a notch 20 adapted to receive the end of a locking hook 21 having a boss 22 and two small pins 23 which can slide and oscillate, in slots 24 of a support 25. The hook 21 is subjected to the action of a spring 26. 55

Moreover, means are provided in order to avoid the accessibility for the consumer to more than one receptacle 5 or 6 at each manipulation.

To this end, the shutter 8 can be opened only if a receptacle 5 or 6 is situated exactly in front of the opening 7 and this result is obtained by a hook 21 which at this moment liberates the general locking hook 21 and which is actuated by a pushing member 23 and a lever 29 submitted to the action of bosses 30 fixed under the plate 4 in positions which correspond to the positions which the receptacles 5 or 6 must exactly occupy to permit the opening of the shutter 8.

Moreover, the plate 4 is prevented from moving as soon as the shutter 8 begins to be opened and to this end, projecting parts 34 are provided under the plate 4 in a number corresponding to the number of the receptacles 5 or 6. The rod 17 has a notch 35 into which fits the extremity 36 of a lever 37 adapted to oscillate about a pivot 38 and subjected to the action of a spring 39. From the lever 37 projects a fork 40 so that when the rod 17 is actuated, it carries along the lever 37 which supports the fork 40 and the latter immobilises the projecting part 34 which is in front of it and consequently also the plate 4.

The coins or counters are introduced through a single slot 31 into a duct comprising a coin selector 32 of known type situated underneath the slot 31 so that counterfeit coins are directed towards a receptacle 33 whilst the good coins penetrate into the coin locking device of the apparatus.

The coin locking mechanism comprises a support 25 which carries at its lower part a duct 41 in which the coins are adapted to be stopped at different heights and being adapted to oscillate around a vertical pivot 43 fixed underneath the support 25. The duct 41 has openings 44, 45, 46 for the passage of stops for the coins.

In each of the openings 44, 45 and 46 project the extremities 48 of movable rods 49¹, 49², and 49³ forming coin stops at different heights in the duct 41. Each rod 49¹, 49², 49³ is curved upwards and forms horizontal branches 50¹, 50², 50³ which terminate—with the exception of the branch 50³—in rollers 51¹, 51² and which are adapted to oscillate about a pivot 52 fixed on the support 25.

The movable plate 4 carries at its central part a cylindrical support 53 which is provided with cams 54 acting on one or the other of the rollers 51¹ or 51². The element 53 is optional as the cams 54 may be supported by any suitable means on the plate 4, for instance they may be supported by the receptacles 5 or 6.

The apparatus so constructed operates in the following manner:

The container 5 or 6 containing the article which has been chosen by the consumer is brought by the manipulation of the handwheel 16 in front of the opening 7 and the number of coins required for the discharge of one article is introduced through the slot 31.

If the container of the article which has been chosen only requires a single coin for the extraction of one article, there is on the support 53 no cam operating on one or the other of the rollers 51¹, 51².

One coin being thus introduced, it is directed into the duct 41 and is stopped in this by the extremity 48 of the rod 49¹. A pull being then exerted on the rod 17, the latter moves and carries

with it horizontally the hook 21, the pins 23 of which slide in the slots 24 of the support 25.

During this horizontal displacement, the boss 22 of the hook 21 comes in contact with the edge of the coin C; the consequence is that the hook 21 is tilted and liberates the rod 17. This permits the opening of the shutter 8 and the removal of the article which has been chosen by the consumer.

Continuing its movement, the rod 17 liberates the duct 41 which under the action of a spring 42 pivots about the axis 43 carrying with it the coin which being no longer supported by the extremity of the rod 49¹ descends in the channel to fall into the coin receptacle of the apparatus. During its return movement, produced by the consumer, the rod 17 meets the duct 41, causes it to oscillate in an inverted direction and brings it back to its original position against a stop 47 of the support 25.

If the price of the article to be distributed necessitates two coins, a cam 54 is located so as to act on roller 51¹ whereby the rod 49¹ is caused to oscillate around the pivot 52 and the extremity 48 of rod 49¹ is withdrawn from the duct 41. When the two coins have been introduced, the first coin is stopped in the duct 41 by the extremity 48 of the rod 49² which has not oscillated and the second coin takes up a position on the upper edge of the first one and can cooperate with the hook 21 in the above described manner.

If the price of the article requires three coins a cam 54 is arranged so as to act on the rod 49² which owing to one claw 55 carries with it the rod 49¹. The extremities 48 of said rods 49¹ and 49² are withdrawn from the duct 41 and the first coin introduced is stopped by the extremity of the rod 49³ whilst the two other coins come one above the other, the last coin of the number which is required cooperating in the above described manner with the hook 21.

It is easy to understand the apparatus may be constructed to operate with a number of coins less or more than three, which permits in the latter case of increasing the variety of the prices of the articles which can be sold. To this end it is only necessary to reduce or to increase the length of the duct 41 and the number of the rods 49 and also of their actuating members.

In order to maintain a complete closure of the shutter 8 when the apparatus is at rest and to ensure a suitable contact between the different elements 16, 16a and 4, the device is so designed that the action of the spring 39 is only felt at the commencement of the opening manipulation and at the end of the closing manipulation so that the consumer should not have to maintain the shutter 8 in its opened position during all the manipulation. This is obtained by the fact that the extremity 36 of the lever 37 is displaced according to an arc of a circle and leaves the notch 35 of the rod 17 in view of the fact that the lever 37 oscillates around the pivot 38. The extremity 36 only comes again into the notch 35 when the latter is in front of it on the return of the rod 17.

The receptacles 6 which can contain each a plurality of articles which can be obtained successively by a separate prepayment for each article comprise a frame 56 forming a box the upper part of which is open. At the bottom of the box there is a radially sliding plate 57 one end of which supports a raised part 60 which, at each distribution of one article can pass through an opening 61 made in the frame 56, ex-

pells the lowest article of the pile and also sustains above the distributing opening 62 the following articles of the pile. The plate 57 is actuated simultaneously with the rod 17 and the shutter 8, for instance by means of a hook 58 which is provided at the other end of plate 57 and which cooperates when it is brought in front of the shutter 8, with a hook 59 fixed on the latter.

10 A movable stop 63 of suitable shape fixed to the box 56 holds in cooperation with the raised part 60 the article of the pile which follows the one which is being distributed.

15 A spring or any other equivalent member 64 exerts constantly a pressure on the pile of articles so as to lower the latter when the bottom element is withdrawn.

20 In order to provide an apparatus comprising receivers for articles of different sizes, the apparatus may comprise shutters which can be opened completely or partially according to the dimensions of the receptacle or of the article being in front of the distributing opening, the extent of the shutter movement being adjusted automatically.

25 In the embodiment according to Fig. 4, the shutter slides parallel to the vertical edge of the base of casing 1. A lever 68 of which one extremity is hinged to the lug 69 fixed to the shutter 8 and the other extremity of which is fixed to a pivot 70 co-operating with a notch 71 of the rod 17, transmits the movement of the latter to the shutter.

30 This system of shutter permits the use of compartments 72 and 73 of different widths and in this case the rod 17 is provided with a projection 74 which can strike against stops 75 provided under the plate 4, thus limiting the stroke of the rod and consequently the width of opening of the shutter.

35 In the embodiment according to Fig. 5, one of the arms of the lever 68 is replaced by a toothed sector 76 co-operating with the rod 17.

40 In this figure, the hook 27 shown in Fig. 1 and also the lever 29 and the bosses 30, do not exist and are replaced by a rib 77 fixed to the plate 4, and by a projecting part 74 fixed to the rod 17. This projecting part can only be introduced into the recess 78 of the rib 77 if a receptacle 5 or 6 is exactly in front of the opening 7. The stroke of the rod 17 may be restricted by reducing the length of the portion 78. The ribs permit the use, with the sliding shutter, of compartments 72 and 73 of different widths.

45 According to Fig. 6, the shutter co-operates with the locking device through a sector 82 to which is connected a flexible transmission 83 fixed on the other hand to the rod 17. This embodiment permits the use of a double flap shutter for compartments having two different widths; in this case, there is provided under the plate 4 a rim 84 provided with notches 85 of relatively small dimensions for the opening of a single flap of the shutter 8, or of notches 86, the dimensions 50 of which are twice those of the notches 85, for the opening of two flaps. Each flap or leaf is provided with a sector 87 having edges 88 adapted to pass into the notches 85 or 86 of the rim, to permit the opening of the shutter.

55 Figs. 7 to 12 show modifications given by way of example of the method of arresting coins in the duct of the locking device.

60 In each of the following embodiments, the duct 41 is in a fixed relation with respect to the support 25.

In the embodiment according to Figs. 7 and 8 the stopping of the coins is effected in the interior of the duct 41 by sliding pins 117¹, 117², 117³ which pass through the duct 41 and which can be actuated transversely in the duct by the rods 6 49¹, 49², 49³ described above under the action of the cams 54.

The pins 117¹, 117² and 117³ have a part 118 of reduced diameter which when brought in the path of the duct allows passage of the coins, 10 whilst the first coin of the number required is arrested by the first pin having its part of greater diameter in the path of the duct.

15 If it is supposed that the price of the article requires two coins, then the rod 49¹ is actuated by a cam 54 and is caused to oscillate; the stop 117¹ can then slide in the sense indicated by the arrow F₂ under the action of a spring 130 and take the position indicated on the drawing. The part of less diameter is placed in the coin path formed 20 by the duct and the first coin which has been introduced is arrested by the part of greater diameter of the stop 117², the second coin being superposed above the first. Afterwards, a movable member (not shown) acts on the rods 49² and 49³ 25 so as to cause them to oscillate and the sliding of the stops 117² and 117³ under the action of their springs 118¹ in the sense of the arrow F₂ brings their parts of reduced diameter into the path of the coins which then fall down into the 30 collector.

35 In the embodiment according to Figs. 9 and 10, the stops are formed as pins 131 which are each provided with a notch 120 and which instead of moving transversely in the duct 41 oscillate in the latter each under the action of a lever 119 integral with the pins. Each lever 119 is actuated by driving members, such as rods, levers, etc., which receive their motion simultaneously or separately from members such as the cams 54 of Fig. 2, 40 corresponding to the receptacle being in front of the distributing opening, the number of stops 131 which are actuated depending upon the number, the position and the dimensions of the said cam or other member. During the opening of the 45 distributing door, a movable member acts on one of the driving members of the levers 119 so as to bring all the pins 117 with their notch into register with the path of the duct, so that the coins are no longer arrested and fall down. 50

55 In the embodiment according to Figs. 11 and 12, the duct 41 is provided with a cylindrical member 121 which projects over the whole of its length into the duct 41. The member 121 is provided with a longitudinal groove 122 which can be 60 brought into register with the slot of the duct.

65 The cylindrical member 121 is furthermore provided with projections or stops 123 which are arranged in a stepped relation and which can project into the duct 41.

The member 121 may be rotated by the cams provided on the receivers. To this end it can be provided with a toothed sector 124 cooperating with a rack 125. The latter may carry at one end thereof a member which is subject to the action 65 of the cam corresponding to the receiver in front of the distributing opening.

70 The importance of the sliding motion of the rack 125 and consequently the amplitude of the rotation of the cylinder 121 is determined, in this 70 example, by the thickness of the corresponding cam.

75 During the opening movement of the door, a suitable movable member actuates the rack 125 so as to cause the cylinder 121 to rotate whereby 75

the longitudinal groove 122 is brought into the path of the duct and the coins, being no longer supported by any of the stops 123, fall down into the collector.

5 Obviously, the casing may have any suitable shape (rectangular, square, circular, etc.), corresponding to that of an ordinary table.

What I claim is:

1. In an automatic vending machine, a stationary casing, a rotatable magazine in said casing, said magazine consisting of a plurality of radially disposed receptacles for various articles having different prices, respectively, a discharge opening in said casing, a door for said opening, 10 means projecting to the outside of said casing for rotating said magazine whereby any of said receptacles can be positioned in front of said discharge opening, locking means for said door including a movable member connected with said door and adapted to be actuated from the outside of said casing and a latch element resiliently engaging said movable member and free to be displaced therewith a short distance at the beginning of the latter's movement, and a coin controlled mechanism for releasing said locking means, said mechanism comprising a coin duct, a plurality of movable stops associated with the coin duct and spaced longitudinally thereof, each of said stops corresponding to one of said different prices and being adapted when in one position to support in said duct a number of edge-wise disposed coins representing said corresponding price with the rim of the uppermost coin projecting into the path of said latch element and forming a cam surface causing disengagement of the latch element from the movable member when the latter is actuated and when in another position to permit passage of coins through the duct, means to move said movable stops, and means associated with the individual receptacles, respectively, and constructed and arranged to actuate the movable means to position the stop means corresponding to the price of the selected article as active coin support in said coin duct when the receptacle containing the selected article has been brought in front of the discharge opening.

2. An automatic vending machine, as claimed in claim 1, in which all said movable stops project normally into said coin duct and the means associated with the individual receptacles include cams mounted on the rotatable magazine, said means for moving the stops comprising levers

projecting with their free ends into the paths of said cams, the cams associated with the individual receptacles, respectively, being shaped and arranged to actuate, upon positioning of a receptacle containing a selected article in front of said discharge opening, the lever of at least one of the stops corresponding to a price less than that of the selected article so as to withdraw from the coin duct all the stops disposed at higher levels than that corresponding to the price of the selected article.

3. An automatic vending machine, as claimed in claim 1, in which said means for moving the stops comprise pivoted two-armed levers, having each one end thereof formed integral with one of said stops, the latter projecting normally into said duct, and said means associated with the individual receptacles include cams mounted on said magazine for engagement with the opposite ends of said levers, the cams associated with the individual receptacles, respectively, being shaped and arranged to actuate, upon positioning of a receptacle containing a selected article in front of said discharge opening, the lever of at least one of the stops corresponding to a price less than that of the selected article so as to withdraw from the coin duct all the stops disposed at higher levels than that corresponding to the price of the selected article.

4. An automatic vending machine, as claimed in claim 1, in which said movable stops are formed as axially slidible pins extending transversely of said duct at one end thereof, each of said pins having a portion of sufficiently reduced diameter to allow passage of the coins past said pin when its reduced portion is brought into register with said duct.

5. An automatic vending machine, as claimed in claim 1, in which said means for moving the stops includes a rotatable cylindrical member disposed parallel to and projecting peripherally into said coin duct, said stops being formed as spirally offset steps in said cylindrical member, and each of said cooperating means is shaped and arranged to cause a rotation of said cylindrical member about a predetermined angle when its associated receptacle is positioned in front of said discharge opening, whereby the stop corresponding to the price of the selected article is brought into operation position in the coin duct.

RENÉ STRA.
